Patented May 9, 1922.

UNITED STATES PATENT OFFICE.

CLIFFORD E. COLE, OF BIRMINGHAM, ALABAMA, ASSIGNOR TO LINKA L. COLE, OF BIRMINGHAM, ALABAMA.

WATER HEATER FOR GAS STOVES.

1,415,527.

Specification of Letters Patent.

Patented May 9, 1922.

Application filed October 20, 1919, Serial No. 332,043. Renewed October 13, 1921. Serial No. 507,490.

To all whom it may concern:

Be it known that I, CLIFFORD E. COLE, a citizen of the United States of America, residing at Birmingham, in the county of Jefferson and State of Alabama, have invented certain new and useful Improvements in Water Heaters for Gas Stoves, of which the following is a specification.

My invention relates to a novel water heater attachment for gas burning stoves.

I have sought by my present invention to design a simple and inexpensive attachment which can be mounted on the top of any ordinary type of gaseous fuel burning stoves and which, without interfering with normal cooking operations thereon, will utilize a large percentage of what would otherwise be waste heat to heat water in a tank with which the attachment is connected.

It is my purpose to utilize a coil suitably mounted in a metal frame adapted to be set on the stove top above the ordinary burners therein and provided with holes of the ordinary size above the burners.

arranged to pass back and forth across the stove holes in the frame with sufficient space between the coils for the practically unobstructed upflow of the flame therethrough from the burners.

One distinctive feature of my invention is the arrangement and manner of attachment of the coils to the frame so that they will serve as a support for cooking vessels smaller in diameter than the holes in the casting.

A further distinctive feature of my invention is the provision of means to regulate the outflow of heat through the holes in the frame to thereby largely confine the flame under the frame and intensify, if desired, its heating effect on the hot water coils, and to this end I provide a novel arrangement of shoulders surrounding the holes and the lid closures therefore which according to their relative adjustment will control the escape of heat from the frame but which are preferably so designed as not to smother the burner in any relative position.

My invention also comprises the novel details of construction and arrangements of parts, which in their preferred embodiment only are illustrated in the accompanying drawings, in which:

Fig. 1 is a plan view of my attachment

mounted on part of a gas burning stove top and showing one lid removed and the other partly broken away.

Fig. 2 is a partial section and partial side elevation of Fig. 1.

Fig. 3 is an enlarged cross sectional view of a part of the stove top and adjustable cover showing the parts in a different position from that shown in the fragmental cross section in Fig. 1.

Fig. 4 is a partial sectional view taken on the line 4—4 of Fig. 3.

Fig. 5 is a bottom plan view of the stove top.

Similar reference numerals refer to similar parts throughout the drawings.

I have shown my invention in connection with a typical gas stove 1 having a top 2 provided with a plurality of holes 3 disposed above gas burners 4. The parts thus far described are typical of any gaseous fuel burning stove and may be widely varied as my invention is adapted to be combined with any type of gas burning stove.

My invention proper comprises a metallic cast frame comprising a top 5 surrounded by a marginal flange 6 which slopes outwardly and at its base is adapted to rest on the top 2 of the stove. In length and width the casting is preferably adapted to cover two burners whether disposed lengthwise or crosswise of the stove. As illustrated, the top 5 is provided with two holes 7 disposed concentric with the holes 3 and burners 4 of the stove. A water coil is mounted in the cast frame and comprises an inlet leg 8 and an outlet leg 9 which are passed through apertures in the flange 6 of the casting adjacent to a hot water tank 10 to which the inlet leg 8 is coupled by a pipe 11 and the outlet leg 9 is coupled by a pipe 12. The two legs 8 and 9 of the coil are parallel and extend lengthwise of the casting and are spaced equi-distantly from the hole centers, the leg 8 being coiled back and forth on the adjacent side of the casting and then connected by a cross leg 13 with similar coils on the other side of the casting which deliver into the outlet leg 9. Coils are on a level so no air can collect to stop circulation, and the water must pass through the entire length of exposed coil piping so that it is very hot at points of exit. Any other suitable arrangement of the coils may be sub-

stituted, but that shown is preferred as interfering least with any other parts of attachments for the gas stove proper.

The coils at each end are rigidly clamped 5 against the top 5 of the casting by clips 14 which underlie the several parts of the coil at their respective ends of the casting and are connected to the top of the latter by countersunk bolts 15 which receive nuts that 10 act to bow the clips between adjacent legs of the coil and thereby hold the latter in relative position as well as to rigidly support them. The coils of the pipe are disposed so as to engage the underface of the 15 top 5 and they are very strongly and rigidly clamped thereto by the clips 14. As will be seen in Fig. 1, at least four legs of the pipe coils are exposed under each hole 7 and their spacing is such as not to materially interfere with the upflow of heat from the burners while furnishing a suitable support for 20 cooking vessels smaller in diameter than the holes 7.

I provide the top 5 with a series of equi-distantly spaced lugs or shoulders 16 which surround each hole 7 and have their inner vertical edges flush with the curved like edge of the hole 7. These lugs are raised about one-half an inch above the level of the 30 casting top 5 and have flat tops on which a marginal rim 17 surrounding the stove lid 18 is adapted to rest. This lid is provided with an annular flange 19 which depends substantially to the level of the casting top 35 5 and in its outer peripheral face I cast a series of equi-distant, open bottom notches 20 which are separated by spacer webs slightly narrower circumferentially than the shoulders 16. Also the outside diameter of 40 the flange 19 is slightly less than the diameter of the hole 7. As a result of this arrangement when the notches 20 are shifted to position directly opposite the shoulders 16, the latter substantially block the outflow 45 of the products of combustion through the notches, permitting just enough to pass to maintain combustion at the burners 4, and under such conditions there is but slight escape of heat from the cast frame which, being closed underneath by the stove top, will 50 effectively hold the heat on all the coils and the efficiency of the heater is at a maximum. As the top is shifted to bring the notches more and more out of register with the shoulders 16, the area of the escape orifices increases until, as shown in Fig. 1 at the right, the notches 20 are practically unobstructed and there is a full and free outflow of the flame around the lid. By this arrangement 55 cooking can be carried on in vessels resting on the lids with a regulated outflow of heat under the lids, or, if desired, the lid may be removed and the vessels set directly on the shoulders 16 or on the coils of the water 60 pipe.

The use of the notched lids and their co-operation with the shoulders 16 is such as to give me a wide range of control of the heat generated by the burners both for water heating and for cooking purposes and enables me to conduct both operations with the maximum efficiency and with the least possible waste of gas.

Having thus described my invention, what I claim as new and desire to secure by Letters Patent, is:—

1. A water heating attachment for gas stoves comprising a casting having a top and marginal flanges forming an open-bottom chamber therein, a water heating coil mounted in the chamber formed under said casting, said casting being provided with openings in its top under which portions of the coil pass, raised marginal lugs surrounding said openings, and a lid closure for said openings having a depending notched flange disposed in juxtaposition to said lugs and adapted to co-operate therewith, as and for the purposes described.

2. In a water heater for gas stoves, an attachment containing a water coil and having holes in its top under which said coil passes, a series of equi-distantly spaced marginal shoulders surrounding said holes and having flat tops, and a lid for each hole having a marginal rim and a depending annular flange adapted to fit a hole loosely, said flange having notches in its outer periphery spaced on the same centers as said shoulders and slightly exceeding the latter in circumferential width.

3. In a water heater for gas stoves, an attachment containing a water coil and having holes in its top under which said coil passes, a series of equi-distantly spaced marginal shoulders surrounding said holes and having flat tops, and a lid for each hole having a marginal rim adapted to set on top of said shoulders and a depending annular flange adapted to fit loosely between said shoulders, said flange having notches in its outer periphery spaced on the same centers as said shoulders and slightly exceeding the latter in circumferential width, and said notched peripheral face of said flange being slightly spaced from the inner faces of said shoulders and corresponding substantially in height with the latter.

4. In a water heating attachment for gas stoves comprising a frame having a flat top with stove holes therein and a marginal down-turned flange adapted to rest on the stove top, a heating coil having its inlet and outlet legs juxtaposed and entering through the side flange on each side of the center of said holes, said inlet leg being connected by a reverse bend to cross leg and said outlet leg being connected by a reverse bend to the said cross leg, all of said coil lying in the same plane juxtaposed to the flat under- 130

surface of the frame, and a cross supporting bar at each end of the frame which is bolted to the top and supports all legs of the coil, substantially as described.

5. A water heating attachment comprising an open-bottom cast frame having a flat top with holes and a marginal flange, a water coil disposed within the chamber in said casting and being coiled back and forth in
10 the same plane, the coil being closely sur-

rounded marginally by said flange and being juxtaposed to the top of the frame, and a common cross support at each end of the frame for the several legs of the coil, substantially as described.

15

In testimony whereof I affix my signature.

CLIFFORD E. COLE.
